UNITED STATES PATENT OFFICE

117,501

DESIGN FOR A SIGN SUPPORTING BRACKET

Louis J. Schneider, Chicago, Ill.

Application September 11, 1939, Serial No. 87,130

Term of patent 7 years

To all whom it may concern:

Be it known that I, Louis J. Schneider, a citizen of the United States and a resident of Chicago, in the county of Cook, State of Illinois, have invented a new, original, and ornamental Design for a Sign Supporting Bracket, of which the following is a specification, reference being had to the accompanying drawing, forming a part thereof, wherein

The figure is a perspective view of a bracket embodying the design of this invention.

I claim:

The ornamental design for a sign supporting bracket, as shown.

LOUIS J. SCHNEIDER.
